UNITED STATES PATENT OFFICE.

SERGE VINCENT DE BOLOTOFF, OF LONDON, ENGLAND.

HYDROCRAFT PLANING-SURFACE.

1,301,917.

Specification of Letters Patent. Patented Apr. 29, 1919.

Application filed February 1, 1918. Serial No. 214,867.

To all whom it may concern:

Be it known that I, SERGE VINCENT DE BOLOTOFF, a Russian subject, engineer of the Russian Naval Aviation, and whose post office address is India House, Kingsway, London, England, have invented certain new and useful Improvements in Hydrocraft Planing-Surfaces, of which the following is a specification.

10 This invention is for improvements in or relating to hydrocraft planing surfaces and has for its object to provide means whereby shock may be absorbed by the planing surfaces. The word "hydrocraft" throughout this specification and claims is intended to cover any craft having planes which co-operate with the water to lift the craft whether such craft also has planes which lift it completely out of the water or not.

15 20 This invention is particularly applicable to hydrocraft of the type wherein planes are provided which are set bodily down below the level of the floating-surface (*i. e.* the underside of the floats or hull) whereby 25 the craft is supported when not in motion, which planes are submerged when the hydrocraft is stationary but lift the hydrocraft as it is driven forward so that the main floating-surface is lifted above the level of the 30 water.

In this type of hydrocraft heretofore employed the planes have been rigid throughout but according to the present invention each such plane comprises a forward and 35 a trailing part whereof the forward part is preferably fixed relatively to the hydrocraft and the trailing part is hinged to swing about an axis that is transverse to the direction of travel and more or less horizontal, the said trailing portion being yieldingly further supported from a point behind the said axis for the purpose herein-after described.

40 It has already been proposed to provide the floating-surfaces, that is the floats or hull, of hydrocraft with planes which are hinged at their forward end to the underside of the floating-surface and are spring-controlled at the trailing end. Although with 45 such an arrangement the body of the float itself provides a fixed plane portion in front of the hinged plane, it offers a large surface to the water and thus is exposed to considerable shock when striking the waves, where- 50 as with the type of craft to which this invention applies, where the planes are set

down below the level of the floating surface, a decrease of shock is obtained as the planes cut through the waves and the floating surface is kept either entirely free of them or only brought into contact with the tops of the larger ones.

55 One method of carrying out this invention is shown in the accompanying drawings in which—

Figure 1 is a side elevation of a hydroplane hull with the pivoted compound plate hereinafter described applied to it,

Fig. 2 is a diagrammatic plan of a pivoted compound plane, showing the supporting stays in section, and

Fig. 3 is a side elevation of the same.

In the drawings the forward portion A of the plane is shown as carried rigidly by the rigid stays D and E, fixed at their upper 75 ends to the hull H of the hydrocraft, while the forward end of the trailing portion B is transversely pivoted or hinged at C to the rigidly-held forward portion A, and the after end is similarly pivoted to the end 80 of the stay F; which stay would in this case be yieldingly carried in any convenient way by the hydrocraft. It may be controlled as in Fig. 1 by a spring S in compression above the top of the stay F in a tube T. Into this 85 tube T the stay F telescopes. The tube is pivoted by a pin P at its upper end to a lug L secured to the hull H. In the lower part of the tube T is a pin t passing through a slot x in the stay F to prevent the stay from 90 being forced too far out of the tube.

The planes may be of any suitable cross-section (that is, a section made in the direction of travel) and have curved or flat surfaces.

95 As shown in Fig. 2, the forward portion A of the compound plane AB is of triangular cross-section, the upper and lower sides A¹ and A² being curved outward and having their apex in the front edge of the 100 plane. The sides A¹ and A² are considerably longer than the base or thickness of the plane at the pivot.

The trailing portion B of the plane is also of triangular cross-section, but the upper 105 and lower sides of the triangle are shown straight and much longer than the sides A¹ and A².

Within a certain speed limit in smooth water, the forward and trailing portions of 110 the compound plane operate like one ordinary rigid plane; but if the water is not

smooth and the plane strikes a wave it can then (if both ends are pivoted as described) yield at either end or both ends as circumstances require.

5. If the speed in smooth water is increased beyond a given point so that the resistance against the trailing portion of the plane becomes such as to overpower the yielding-control therefor, then the said trailing portion can swing up about its hinged connection against the action of the yielding-control and thus decrease the angle at which it is presented to the water so that the resistance of the latter to it does not continue 10 to increase with the increase of speed in the same proportion as would be the case if no such yielding movement were possible.

Again, when the craft is alighting upon the water, the tail-portions of the planing 20 surfaces will touch the water first and these can then yield to absorb shock at the moment of alighting.

What I claim as my invention and desire to secure by Letters Patent is:—

25. 1. In a hydrocraft, the combination of, a composite plane comprising leading and trailing portions respectively, means to support the plane from the hydrocraft in such position that it is situated bodily below the 30 level of the "floating-surface" of the hydrocraft, means for hinging the said trailing-portion at its forward end relatively to the leading-portion and the supporting-means, to swing about an axis that is transverse to 35 the direction of travel and more or less horizontal, and yielding means operatively connecting the said trailing-portion to the

supporting-means at a point behind the said axis of hinging, for the purpose described.

2. In a hydrocraft, the combination of, a composite plane comprising leading and trailing portions respectively, means to support the plane from the hydrocraft in such position that it is situated bodily below the level of the "floating-surface" of the hydrocraft, means for rigidly securing the leading part of the composite plane to the said supporting-means therefor, means for hinging the said trailing-portion at its forward end relatively to the leading-portion and the 50 supporting-means, to swing about an axis that is transverse to the direction of travel and more or less horizontal, and yielding means operatively connecting the said trailing-portion to the supporting-means at a 55 point behind the said axis of hinging, for the purpose described.

3. In a hydrocraft, the combination of, a composite plane comprising leading and trailing portions respectively, means to support the plane from the hydrocraft in such position that it is situated bodily below the level of the "floating-surface" of the hydrocraft, means for hinging the said trailing-portion by its forward end to the rear of the 60 leading-portion to swing about an axis that is transverse to the direction of travel and more or less horizontal, and yielding-means operatively connecting the said trailing-portion to the supporting-means at a point behind the said axis of hinging, for the purpose described.

In testimony whereof I affix my signature.
SERGE VINCENT DE BOLOTOFF.
